UNITED STATES PATENT OFFICE.

PHILIP LANG, OF CEDAR FALLS, IOWA, ASSIGNOR TO WAGNER MANUFACTURING COMPANY, A CORPORATION OF IOWA.

ELEVATOR-DOOR-OPERATING MECHANISM.

Application filed August 1, 1922. Serial No. 579,001.

My invention relates to improvements in elevator door operating mechanism.

The object of my invention is to provide an operating means for double doors for elevators which practically eliminates the noise usually found in such doors, and which is accomplished by flexible chains or cables or the like and maintaining both ends, connected to the different doors, under equal tension.

Another object of my invention is to absolutely prevent the possibility of any accidental interference of any of the movable parts with one another or with any of the stationary parts and also prevent any sagging of the flexible operating means or side lash thereof and thus obtain as nearly as practical a noiseless door.

Another object of my invention is to provide an operating means in which any loose connection of the door or the operating part is automatically taken up and thus produce an operating means having a material advantage over those now on the market.

A still further object of my invention is to provide a simple, cheap and effective operating means of this character having certain details of structure and combination of parts hereinafter fully set forth.

In the accompanying drawings:—

Fig. 1 is a side elevation of a sliding elevator door with my invention applied thereto;

Fig. 2 is a top plan view of Fig. 1;

Fig. 3 is a top plan view similar to Fig. 2 showing my invention applied to a four door arrangement;

Fig. 4 is a transverse sectional view taken on the line 4—4 of Fig. 1;

Fig. 5 is a transverse sectional view taken on the line 5—5 of Fig. 3.

Referring now to the drawings, 1 represents the track arranged at the opening in the elevator shaft and which as shown is formed of two U-beams 2 and 3 bolted together by bolts 4 having the washer 5 between the same, so as to form the space 6 between the same, the purpose of which will be later described. The track as will be understood extends slightly beyond the door opening. The inner U-beam 2 is supported to the wall of the elevator shaft by means of brackets 6' as shown in Fig. 4 of the drawings. While I have shown and described this specific form of track it will be under-

stood that any form could be used provided provision was made for the ball or roller carrying plate, so that the same prevents the transverse movement of the roller carrying plate.

In the form shown in Figs. 1—2 and 4 of the drawings, the doors 7 and 8 are secured to the hangers 9 and 10 by bolts 11 and said hangers are connected by bolts 12 to the door carrying beam 13. This beam as indicated at 13, Fig. 4, is formed by two U-beams 14 and 15 bolted together and having their inner abutting walls at their lower ends cut away as indicated at 16 and 17 to form the longitudinal groove 18 in its lower face. The ball carrying plate comprises a plate bar 19 arranged on edge in a vertical position and having at proper intervals the struck out portions 20 and 21 arranged on each side forming ball retainers 75 for the balls 22 and whereby the carrier is free to travel on the track with the plate between the U-beams 4 and also in the groove 18. These balls are free to rotate in the plate and whereby a free and even rolling action of the beam 13 is permitted. There is no positive connection between the ball carrying plate and hanger beam, but the said beam is provided with downwardly extending arm 23 adapted to engage the lug 80 24 carried by the ball carrying plate when the door is moved in one direction and to engage the lug 25 carried by the plate when moved in the opposite direction, all of which will be later described.

As heretofore described each door 7 and 8 is provided with two hangers 9 and 10 rigidly secured to their respective beams. The track at its ends is provided with pulleys 26 and 27 over which passes the two 95 cables 28 and 29. These cables can be of any desired form and can be in the form of a chain if desired. The inner hanger of each door is provided with brackets 30—31 bolted or otherwise secured thereto and having laterally turned ends 32. Secured to the laterally turned portion of the bracket 31 is a coiled spring 33 which has its opposite end secured to the cable 28. The cable 28 as described passes over the pulley 26 100 and has its other end secured to the bracket 30 carried by the hanger 9 of the door 7. Also secured to the bracket 30 is a coil spring 34 which has its opposite end secured 105 to the cable 29. The said cable passes over 110

the pulley 27 and has its opposite end secured to the bracket 31 carried by the hanger 9 of the door 8.

By this structure it will be seen that upon the operation of either door the other door is simultaneously operated. This is accomplished in the following manner. The door 7 is moved to the right as indicated by the arrow in Fig. 1. This movement of the door pulls on the cable 28, it being attached to the bracket 31 of the hanger 9 of the door 8. This starts the door 8 to move in the opposite direction as indicated by arrow, Fig. 1. The spring 34 gives door 7 a gradual starting movement and at the same time the cable 28 is holding the spring 33 under tension and the doors are simultaneously moved in the opposite direction under spring tension from both ends whereby a gentle starting of the door is obtained without practically any noise.

The supports of the hangers roll on the balls and travel twice the distance than the balls themselves and the plate in which they are enclosed; thereby causing the balls to partially follow the carrying beams in the direction of travel and thus make it possible to use a shorter ball train than the length of the track. In case the motion of the ball retainer plate, in either direction, is impeded and the door carrying beam caused to slide over the balls, then towards the end of travel of the door carrying beam, the arm 23 abuts against either of the lugs 24, causing thereby the ball retaining plate to correct its location with regard to the door carrying beam.

In the modification shown in Figs. 3 and 5, I have shown a four door arrangement embodying my invention. In this form the two tracks 35 and 36 are constructed in precisely the same manner as that shown and described in respect to the track 1. These tracks as shown are arranged side by side 40 in the same horizontal plane and are preferably supported by the brackets 37. In this form two doors travel in one direction and two doors in the opposite direction and in Fig. 3 I have shown two doors moving 45 in one direction, the other two doors being broken away but it will be understood that the operation of each pair of doors will be the same. The two doors carrying beams 38 and 39 are constructed the same 50 as that shown in the two door construction and the ball retaining plates 40 and 41 are constructed the same as heretofore described. The hangers 42 and 43 of the outside door are secured to the beam 39 and the hangers 55 44 and 45 of the inside door extend upwardly on the inside of the inner track and secured to the beam 38 as shown in Fig. 5 of the drawings. Secured to the inner beam 38 of the inside door are two brackets 46 60 and 47 which extend down and are secured to

the ball retaining plate 41 of the outside door as shown in Fig. 5.

The outer track at each end is provided with the pulleys 49 the same as shown and described in the preferred form and passing over the same are the cables 50 which are connected to the brackets 51 of the outside door hangers the same as shown in the preferred form so that as either of the middle doors are moved outwardly the other door is moved outwardly. 70 75

By this structure it will be seen that the operation of either of the outer doors will simultaneously start the other outer door to move, and the beams 39 rolling on the 80 balls will travel twice as far as the balls themselves and the plate 41 in which they are enclosed. The beams 38 being connected by the brackets 46 and 47 with the ball retaining plate are caused to travel with and 85 at the same speed as the retaining plate 41, which is half the speed and consequently half the distance that the outer door beams travel. By this means the outer and inner doors of each set when open, starting from 90 a position, side by side at the end of the track will move to a position edge to edge as in Figure 3, when the doors are closed. Likewise the outer doors will travel at twice 95 the speed of the inner doors and having traveled twice the distance arrive simultaneously with the inner doors at the end of the track.

I claim:

1. The combination with two sets of sliding doors, a ball carrying plate for each door, cables connected to the outer door of one set and extending in opposite directions around pulleys and having their opposite ends having a spring connection with the outer door of the other set and operating means carried 100 by the ball carrying plates of the outer door of each set. 105

2. The combination with two sliding doors moving in opposite directions, cables connected to one door and extending in opposite 110 direction around pulleys and spring connection with the other door and means for causing the inner door to travel at half the speed of the outer door.

3. The combination with two sets of sliding doors, cables connected to the outer door of one set and extending in opposite direction around pulleys and having a spring connection with the outer door of the other set and means for allowing of a fast movement 115 of the outer doors of each set so that both doors reach their limit of movement in either direction at the same time. 120

4. The combination with two tracks arranged side by side, four ball carrying plates 125 rolling on said tracks, four door carrying members rolling on said balls of the plate, a spring tension cable attached to the door carrying member of one of the outer doors and extending around a pulley and con- 130

nected to the door carrying member of the other outer door, a spring tension cable connected to the last mentioned door carrying member and extending around a pulley and connected to the first mentioned door carrying member connections between the rear door carrying members and the ball carrying plates on the outer tracks and engaging members carried by the outer door carrying members and adapted to engage lugs carried by the ball bearing plates whereby the moving of one of the outer doors causes the other outer door to move by the cables at a rapid speed so that all of the doors reach their limit of movement in either direction at the same time.

5. In combination with two tracks arranged side by side, ball carrying plates rolling on said tracks, door carrying members rolling on said balls of the plates, a cable connected to the door carrying member

of one of the outer doors and extend around a pulley and connected to a spring connected to the door carrying member of the other outer door, a cable connected to the last 25 mentioned door carrying member and extending around a pulley and connected to a coil spring, connected to the first mentioned door carrying member, connected between the rear door carrying member and the ball 30 carrying plates on the outer track and engaging members carried by the outer door carrying member and adapted to engage lugs carried by ball bearing plates whereby the moving of one of the outer doors causes the other outer door to move by the cables at a rapid speed so that all of the doors reach their limit of movement in either direction at the same time.

10. In testimony whereof I affix my signature.

PHILIP LANG.
